UNITED STATES PATENT OFFICE

WILLIAM W. DASHNER, OF LOGANSPORT, INDIANA, ASSIGNOR TO R-B-M MANUFACTURING CO., OF LOGANSPORT, INDIANA, A CORPORATION OF INDIANA

CIRCUIT BREAKER

Application filed July 8, 1929. Serial No. 376,557.

This invention relates to circuit breakers, more particularly to circuit breakers for use with electrical toys.

Electrical toys, such as electric trains, toy 5 motors, and the like, are usually driven by current derived from a transformer connected to the house lighting circuit. These toys operate on a relatively low voltage supplied by the transformer, and, in case of a 10 short circuit, such as would be caused by a part of the train jumping the track, the transformer supplies a high current to the short circuit. If allowed to continue for any 15 length of time, this current will overheat and damage the transformer and also is liable to damage the toy itself, or to start a fire.

In my co-pending application, Serial No. 367,262, filed May 31, 1928, now Patent 1,824,125, issued September 22, 1931, I dis- 20 close a circuit breaker constructed as a self contained unit to be added to an existing electrical toy installation and arranged to be inserted in the secondary circuit of the trans- 25 former therefor and to open that circuit when the current in it becomes excessively high, as in the case of a short circuit or the like.

The present invention relates to a new and improved circuit breaker of the class de- 30 scribed in the above mentioned co-pending application, the improvements tending to 35 make the circuit breaker more reliable in its operation and, at the same time, cheaper to manufacture.

The present circuit breaker comprises a 40 pivoted armature having a pole piece dis- 45 posed at one of its ends and a contact mem- ber at the opposite end. An electromagnet is disposed in juxtaposition to the pole piece of the armature, and a contact spring in juxtaposition to the contact member on the armature. The circuit breaker is set man- 50 ually by a lever attached to the armature and projecting through the cover of the circuit breaker so that the circuit through the break- 55 er may be closed. When the current in this circuit becomes excessive, the electromagnet attracts the pole piece and thereby operates the armature to open the circuit by moving the contact on the armature away from the 60 spring with which it is associated.

The armature is a dead armature, that is, no spring or other tension devices are em- 65 ployed to govern its movement, so that when the electromagnet operates it to open the cir- 70 circuit, the armature remains in position with the circuit open after the electromagnet has become deenergized.

The armature is pivoted to move about a 75 horizontal axis, and the armature and brackets associated with it are all formed of 80 simple parts, thereby reducing the cost of manufacture of the breaker.

To acquaint those skilled in the art with the teachings of my invention, reference is 85 made to the accompanying drawing in 90 which:—

Fig. 1 is a plan view of a completely as- 95 sembled circuit breaker;

Fig. 2 is a plan view of the circuit breaker 100 with the cover removed;

Fig. 3 is a side elevational view of the 105 breaker;

Fig. 4 is an end view of the breaker; and

Fig. 5 is a cross sectional view taken along 110 the line 5—5 of Fig. 2.

The completely assembled circuit breaker, 115 shown in Fig. 1, is encased in a boxlike cover 1, that cover being attached to the base plate 7 of the breaker by suitable fastenings 5 and 6. These fastenings may be screws, rivets, or 120 eyelets, depending upon conditions under which the breaker is to be used, the eyelets being the preferable form of fastener, since their use permits the insertion of a mounting 125 screw through the eyelet to mount the circuit breaker upon a suitable base or support.

The upper surface of the cover 1, is pro- 130 vided with a slot 2 through which the operat- 135 ing lever 3 of the circuit breaker is projected.

A nameplate 4 is attached to the cover adja- 140 cent this slot 2. This nameplate carries, in 145 addition to the customary nameplate data, the notations "Off" and "On", these notations being placed adjacent the slot as a guide 150 indicating the position of the breaker rela- 155 tive to the open or closed condition of the circuit through it.

The baseplate 7 and the cover 1 are prefer- 160 ably sheet metal punchings formed to the 100

required shapes, the metal preferably being iron.

The operating parts of the circuit breaker are mounted upon a sub-base 21, which is 5 preferably made of an insulating material and is attached to the base 7 by suitable eyelets or rivets.

The circuit breaker comprises the electromagnet 24, the pivoted armature 10 having 10 the pole piece 17 disposed adjacent to the electromagnet 24, and having the insulating block 11 attached to the opposite end of it by the rivets 12 and 13. A spring 18 is supported on a bracket 19 in juxtaposition to the 15 insulator 11 and the rivet 12 which attaches it to the armature 10. The bracket 19 is attached to the sub-base 21 by suitable rivets or eyelets 20.

The armature 10 is also provided with the 20 foot-like projection 14 which extends downward from the insulator 11 adjacent to the sub-base 21.

The lever 14 strikes against the sub-base 25 21 to limit the rotation of the contact carrying end of the armature 10 downward toward the sub-base. The arm 14 is designed so that when it strikes the sub-base 21 the contact spring 18 is then in engagement with the rivet 12, to thereby close an electrical circuit 30 from the contact spring to the armature 10.

The armature 10 is pivoted by the pivot 15 to the bracket 16, which bracket is attached to the sub-base 21 by suitable means, such as eyelets or rivets. The pivot 15 may be a rivet, 35 or a bolt, and, in either case, it tightly holds the armature 10 against the bracket 16 with considerable pressure, so that there is an appreciable friction in the pivoted joint, and the armature is thereby restrained from free 40 movement.

The free movement of the armature is further limited by the arrangement of the contact spring and the rivet 12 which it engages when the armature has been rotated to 45 the position in which the arm 14 engages the sub-base 21. As will best be seen in Fig. 5, the end of the spring 18 is formed in a cup-like section 18', which engages the eyelet 12 and fits and projects into its open end. The 50 spring 18 is tensioned so that it exerts a pressure on the eyelet longitudinally of the axis of the eyelet, and by this the engagement is around the rim of the eyelet and the cup-like portion 18' of the spring, and movement 55 of the armature 10 is resisted thereby.

As will be seen in Fig. 5, when the armature 10 is moved upward, spring 18 must be moved to the left against its tension, the surface of the cup-like portion 18' riding over 60 the open end of the eyelet 12 meanwhile.

The combined resisting action of the friction of the armature 10 with the plate 16 and of the tension of spring 18 are relied upon to 65 hold the armature in the position in which it closes the contact through the spring 18 dur-

ing the flow of the normal operating current of the toy through the electromagnet 24. That is, this tension must be sufficient so that the armature will not operate to open the circuit of the toy when the normal operating current of the toy is flowing through it. Furthermore, the resistance to movement of the armature 10 must not be so great that the electromagnet 24 will be unable to operate it when an abnormally large current flows through the toy, for such condition would defeat the purpose of the circuit breaker.

The electromagnet 24 is mounted upon a foot-like bracket 22 which, in turn, is attached to the sub-base 21 by suitable rivets 23. The electromagnet comprises the usual core with a copper wire wound thereon in the form of a helix. Preferably, this wire is of relatively large cross section so that the resistance of the magnet is low, and its inclusion in the circuit in series with the toy will not materially reduce the voltage delivered to the toy.

The magnetic circuit of the circuit breaker is very loosely connected, there being an appreciable air gap between the end of the core of the electromagnet 24 and the pole piece 17 of the armature 10. The mounting bracket 22 upon which the core of the electromagnet 24 is attached, does not come in engagement with the bracket 16 upon which the armature is attached, the space between the two interposing an additional air gap in the magnetic circuit of the armature. Flux generated in the electromagnet 24 spans the air gap into the pole piece 17, flows through that pole piece and the armature 10 into the bracket 16, flows across the auxiliary air gap from the bracket 16 into the bracket 22 and from there into the core of the electromagnet. The looseness of this magnetic circuit insures that a very strong energization of the electromagnet 24 must be realized before that electromagnet can attract the armature to open the electrical circuit through it.

The electrical circuit of the circuit breaker is conducted into the breaker through the wire 30, which is attached to the bracket 22 by soldering or clamping at the rivet 23. The circuit is conducted from the circuit breaker by the wire 31 similarly attached to the bracket 19 by soldering or riveting to the rivet 20.

The circuit in the breaker itself comprises a connection from the one end 32 of the electromagnet 24 to the bracket 22, and a connection from the opposite end 33 of the electromagnet 24 to the bracket 16.

When the armature is rotated so that the contact spring 18 makes contact with the eyelet 12 and the armature 10 therethrough, the electrical circuit is complete from the wire 30 through the electromagnet 24 through the bracket 16, from the bracket 16 through the armature 10, from the armature 10 through the eyelet 12 to the contact spring 18, and

from the contact spring 18 and the bracket 19 to the wire 31 leading from the breaker.

Preferably, the circuit breaker is included in series with the toy, that is in series with the secondary winding of the transformer that supplies current to the electrical toy. In the normal operation of the toy, the current flowing through the circuit breaker is not sufficient to build up a sufficient flux in the electromagnet 24 to cause it to attract the pole piece 17 of the armature. However, if the toy, such as an electrical train, for example, draws an excessively large current, as would be the case when the train jumps the track and short circuits the rails, the electromagnet becomes sufficiently strong to attract the pole piece 17 and to rotate the armature about its pivot 15.

This rotation of the armature moves the contact spring 18 out of engagement with the eyelet 12 and into engagement with the insulator 11 which is riveted to the armature.

The electrical circuit through the breaker is thereby opened and the toy protected from injury.

The armature 10 is provided with a reset lever 3 which is preferably made of an insulating material and attached to the armature by rivets or other suitable means. This lever projects through the slot in the cover as hereinbefore pointed out, and, since it is disposed adjacent to the "Off" and "On" markings on the nameplate, it serves as a visual indicator for indicating the open or closed condition of the circuit through the breaker.

After this circuit has been opened by an overenergization of the electromagnet 24, it is necessary to manually operate the armature through the reset lever 3 to again close the circuit. This manual operation of the lever rotates the armature about its pivot in the opposite direction, and recloses the circuit.

Inasmuch as the brackets 22, 16 and 19 are included in the electrical circuit, it is necessary that the rivets which attach these brackets to the insulating sub-base 21 be protected so that they do not come in contact with the metallic base plate 7 on which the sub-base is attached. If the rivets or other attaching means employed to attach these brackets to the sub-base were permitted to come in contact with the metallic base 7, the circuit breaker would obviously be short circuited and, therefore, inoperative.

To guard against such short circuiting of the breaker, I have provided a thin insulating strip 26 disposed between the insulator 21 and the metallic plate 7, that insulator 26 preventing the heads of the rivets disposed on the plate side of the sub-base 21 from coming in contact with the plate 7.

From the foregoing, it will be apparent that I have provided a new and improved

circuit breaker of simple yet rugged design, capable of being cheaply manufactured and used to protect electrical toys and the like from damage due to overload.

While I have chosen to show a preferred embodiment of my invention, I have done so by way of example only, as there are many modifications and adaptations which can be made by one skilled in the art without departing from the teachings of the invention.

Having thus complied with the statutes and shown and described a preferred embodiment of my invention, what I consider new and desire to have protected by Letters Patent is pointed out in the appended claims.

What is claimed is:—

1. In a circuit breaker of the class described, a base, a bracket mounted thereon, an armature pivoted at its midpoint to said bracket, an electromagnet disposed on said base and adjacent one end of said armature and operable to move the armature in one direction about its pivot, a second bracket on said base, a spring mounted thereon and engaging said armature to close an electrical circuit through said armature and the bracket upon which the same is mounted, an insulator on said armature engaged by said spring after the armature has been moved by said electromagnet, a lever attached to said armature for manually moving it about its pivot in the opposite direction to reestablish said circuit through it, means cooperating with said lever to indicate the position of said armature, and a projection on said armature arranged to strike said base to limit the movement of said armature by said lever.

2. In a circuit breaker of the class described, a metallic base plate, an insulating sub-base attached thereto, a plurality of brackets mounted on said sub-base, an armature pivoted to one of said brackets, said armature having a pole piece and a stop lever disposed on opposite sides of said pivot, an electromagnet attached to a second of said sub-base brackets and disposed in juxtaposition to said pole piece, said magnet acting on the pole piece responsive to a certain degree of energization to move the armature in one direction about its pivot, an insulator riveted to said armature adjacent said stop lever, a spring mounted on another of said brackets and engaging said insulator after said armature has been rotated by said magnet, a cover for said breaker mounted on said base and having a slot in one of its faces, and a lever on said armature and projecting through said slot, said lever indicating the position of the armature and being operable to rotate the armature in the opposite direction to move one of the rivets which hold the insulator to said armature into engagement with said spring to close a circuit through the armature and the bracket upon which the same is mounted.

120
125
130

said stop lever then stopping the movement of said armature.

3. An overload circuit breaker for electrical toys comprising, a base, an electromagnet mounted upon said base, a bracket mounted on the base adjacent said magnet, an armature pivotally mounted on said bracket, an insulator, rivet means attaching said insulator to the free end of said armature, a second bracket mounted on said base adjacent the free end of said armature, a spring attached to said second bracket and engaged with said insulator when said armature is engaged with said electromagnet, a lever attached to said armature for moving it about its pivot away from said magnet to thereby bring said spring into engagement with said rivet means to establish an electrical connection between the spring and armature, said circuit breaker including means for establishing an electrical connection between said armature bracket and one end of said electromagnet, and conductors connected to the other end of said electromagnet and to said second bracket to permit connecting the breaker in circuit with the toy, said electromagnet operating the armature responsive to an overload condition to open the electrical connection between said spring and armature, a cover for said breaker having a slot through which said lever projects and means on the cover cooperating with the lever to indicate the open or closed condition of said circuit.
35. In witness whereof, I hereunto subscribe my name this 27th day of June, 1929.

WILLIAM W. DASHNER.
